US00D876296S

(12) United States Design Patent (10) Patent No.: US D876,296 S
(45) Date of Patent: * Feb. 25, 2020

(54) VEHICLE HOOD

(71) Applicant: HONDA MOTOR CO., LTD.,
Minato-ku, Tokyo (JP)

(72) Inventor: Daisuke Toriyama, Rancho Palos
Verdes, CA (US)

(73) Assignee: HONDA MOTOR CO., LTD., Tokyo
(JP)

() Term: 15 Years

(21) Appl. No.: 29/668,258

(22) Filed: Oct. 29, 2018

(51) LOC (12) Cl. 12-08

(52) U.S. Cl.

USPC D12/173

(58) Field of Classification Search

USPC D12/86, 90–92, 173

CPC B62D 25/10; B62D 25/06; B62D 65/02;
B62D 25/12; G60Q 1/00

CLAIM

The ornamental design for a vehicle hood, as shown and described.

DESCRIPTION

FIG. 1 is a rear left perspective view of a vehicle hood showing my new design;

FIG. 2 is a rear right perspective view of the design shown in FIG. 1;

FIG. 3 is a front right perspective view of the design shown in FIG. 1;

FIG. 4 is a front left perspective view of the design shown in FIG. 1;

FIG. 5 is a rear view of the design shown in FIG. 1;

FIG. 6 is a front view of the design shown in FIG. 1;

FIG. 7 is a right side view of the design shown in FIG. 1;

FIG. 8 is a left side view of the design shown in FIG. 1;

FIG. 9 is a top view of the design shown in FIG. 1; and,

FIG. 10 is a bottom view of the design shown in FIG. 1.

1 Claim, 10 Drawing Sheets
